UNITED STATES PATENT OFFICE.

WALTER M. HENLEY, OF BRADLEY, ALABAMA.

STIRRUP-LEATHER.

No. 889,604.

Specification of Letters Patent.

Patented June 2, 1908.

Application filed June 27, 1907. Serial No. 381,120.

To all whom it may concern:

Be it known that I, WALTER M. HENLEY, a citizen of the United States, residing at Bradley, in the county of Escambia, State of Alabama, have invented certain new and useful Improvements in Stirrup-Leathers; and I do hereby declare the following to be a full, clear, and exact description of the invention, such as will enable others skilled in the art to 10 which it appertains to make and use the same.

This invention has reference to stirrup leathers, and has for its object the formation from a single strip of leather of an article of that class in which the position of the stirrup 15 with respect to the saddle may be adjusted without necessitating any disarrangement of the sweat-leather.

A further object includes the construction of a stirrup leather, as above described, without the use of any buckles, rivets, or stitching whatever.

To this end, the invention consists in the construction, combination, and arrangement of parts, all as hereinafter fully described, 20 specifically claimed, and illustrated in the accompanying drawings, in which—

Figure 1 is an elevation of the stirrup leather, showing the stirrup in place. Fig. 2 is a longitudinal vertical section taken on the 30 line 2—2 of Fig. 1. Fig. 3 is a plan view of the blank from which the stirrup leather is formed.

Like parts are designated by corresponding reference numerals in the several views.

Referring to the drawings, and more particularly to Fig. 3, it will be seen that the stirrup leather is constructed from a single strip of leather comprising upper and lower tongues 5 and 6, respectively, and an intermediate laterally enlarged portion 7, which last mentioned part serves as the sweat-leather when the device is in use. It will be further noticed in said figure, that the length of the lower tongue is considerably greater 45 than that of the upper tongue, and that the latter is slightly wider than the former—in actual practice, one inch. The upper tongue 5 is provided adjacent its free end with three transverse slots 8 forming the straps 9 and 50 10, the width of the former of which slightly exceeds that of the latter, while the enlarged central portion 7 is provided towards its lower end with a similar strap 11 formed by the transverse slots 12.

In the practical use of the device, the lower

tongue 6 is passed through the slot 13 in the stirrup 14, and is then drawn upwardly through the strap 11; the upper tongue 5 is then bent downwardly and the lower tongue drawn over the outer face of such down-bent 60 portion and passed through the lowermost slot 8 therein, along the inner face, and outwardly through the uppermost slot 8, being then bent backwardly again, and drawn downwardly over strap 9 and under, or 65 through, strap 10, the free end of tongue 6 being finally passed under strap 11 and retained in place therein between the under face of said strap and the outer face of the first upward bent portion of said tongue. 70

When it is desired to increase or decrease the length of the present stirrup-leather, it is only necessary to withdraw the lower tongue from the several straps, and adjust the position of the stirrup thereon, when the tongue 75 is again passed upwardly through the straps, as above described, and held in place thereby, the arrangement of straps permitting such adjustment without altering the position of the sweat-leather. It is further to be noted 80 that the several parts of the device are formed from a single strip of leather, and are held together in operative position without the use of any rivets, pins, buckles, or stitching. 85

What is claimed, is—

1. A stirrup-leather comprising upper and lower tongues and an intermediate sweat-leather formed from a single strip of material, and means formed integrally with said upper 90 tongue and said sweat-leather for holding the several parts in operative position.

2. A stirrup-leather comprising upper and lower tongues and an intermediate sweat-leather formed from a single strip of material, 95 and straps formed integrally with said upper tongue and said sweat-leather for holding the several parts in operative position.

3. A stirrup-leather comprising upper and lower tongues and an intermediate sweat-leather formed from a single strip of material, said upper tongue being of less extent than said lower tongue and provided with a pair of integral transverse straps, and an integral transverse strap formed upon said sweat-leather, and serving with said first mentioned straps to retain the several parts in operative 100 position. 105

4. A stirrup-leather comprising a sweat-leather provided with integral tongues at its 110

upper and lower ends, and with a transverse strap, and a pair of transverse straps formed on the upper tongue, said upper tongue being adapted to be bent downwardly, and said 5 lower tongue to be bent upwardly, and passed through the straps upon the sweat-leather and the upper tongue.

In testimony whereof, I affix my signature, in presence of two witnesses.

WALTER M. HENLEY.
